(57) **CLAIM**

I claim the ornamental design for a ceiling tile, as shown and described.

DESCRIPTION

FIG. 1 is a front, top and left perspective view of the ceiling tile showing my new design;
FIG. 2 is a front elevational view thereof;
FIG. 3 is a rear elevational view thereof;
FIG. 4 is a top side view thereof;
FIG. 5 is a bottom side view thereof;
FIG. 6 is a right side view thereof;
FIG. 7 is a left side view thereof;
FIG. 8 is a cross-sectional view taken along section line 8-8 of FIG. 2;
FIG. 9 is an enlarged right end view of FIG. 8;
FIG. 10 is a front, top and left perspective view of a second embodiment of the invention shown in FIG. 1;
FIG. 11 is a front elevational view of the embodiment of FIG. 10;
FIG. 12 is a rear elevational view of the embodiment of FIG. 10;
FIG. 13 is a top side view of the embodiment of FIG. 10;
FIG. 14 is a bottom side view of the embodiment of FIG. 10;
FIG. 15 is a right side view of the embodiment of FIG. 10;
FIG. 16 is a left side view of the embodiment of FIG. 10;
FIG. 17 is a cross-sectional view taken along section line 17-17 of FIG. 11; and,
FIG. 18 is an enlarged right end view of FIG. 17.

1 Claim, 10 Drawing Sheets
